MEANS FOR MINIMIZING HARMONICS IN RADIO RECEIVER OUTPUT CIRCUITS

Application filed October 10, 1928, Serial No. 311,530. Renewed May 13, 1933.

My invention relates to electrical-discharge devices and particularly to electrical-discharge devices which employ hot cathodes.

One of the objects of my invention is to provide an electrode structure of such type that there is no perceptible fluctuation of an audible frequency in the output current of the tube.

Another object of my invention is to provide an electrical-discharge tube with a thermionically-emissive electrode so rigidly spaced relative to the other electrodes therein that there is not perceptible vibration of the frequency within the range of audibility.

A further object of my invention is to provide a radio tube having a hot-cathode filament so rigidly supported that there is no perceptible noise produced in sound-reproducing apparatus connected in the output circuit of said tube when the latter is subjected to the mechanical shocks and jars incident to its ordinary use.

Other objects of my invention will be apparent upon reading the following specification taken in connection with the drawing, in which Figure 1 is a view, partially in elevation and partially in longitudinal section, of a radio tube having a hot-cathode filament supported in accordance with the principles of my invention.

Fig. 2 is a view similar to Fig. 1, but the parts in section being on line II-II of that figure.

Fig. 3 is a transverse sectional view of the device shown in Figs. 1 and 2.

Fig. 4 is a diagram employed in the following explanation of certain features of my invention.

Fig. 5 is a diagrammatic view of a circuit arrangement in which my invention may be embodied.

The hot-cathode filaments adapted for use with radio tubes of relatively low voltage and small current output, such as amplifiers and detectors for radio sets, are necessarily spaced at relatively small distances from their cooperating grid and plate electrodes. Likewise, economy of heating current makes it necessary that the lengths of the filaments themselves shall be large relative to their diameters. Consequently, such filaments are readily set into mechanical vibration by even the slight shocks and jars incident to their normal use. As a result of these vibrations, the distance separating the filaments from the

plate and grid electrodes varies periodically and, since the impedance to current flow is largely dependent upon this distance, the output current of the tube undergoes similar periodic vibrations, although the supply voltage of the source supplying it is absolutely constant.

The more sensitive the receiving set in which the tubes are to be used, the greater the difficulty resulting from fluctuations of output current, because the summation of all the fluctuations in the output currents of each tube in a receiving set appears in the current operating a loud speaker or other sound-reproducer; and, if the foregoing mechanical vibrations are of audible frequency, a distinct sound, generally known as microphonic hum results. It is, accordingly, very necessary that mechanical vibrations of the electrodes generally, and particularly of the hot-cathode filaments, shall be reduced to the minimum possible value, at least as regards those within the range of audible frequencies.

It has been possible, for some time, to produce radio tubes of sufficient capacity for use as detectors and amplifiers in household radio receiving sets which require the output of only a single dry battery cell to heat the cathodes to their operating temperature. Such tubes usually have cathodes from $\frac{1}{8}$ to $\frac{1}{4}$ of an ampere at 1.1 volts to heat them to their best operating temperatures. Such cathodes are usually made by coating metallic-base filaments with oxides of the alkali earths and it has been possible, by proper selection of the available materials, to produce cathode filaments to meet the requirements that have a length of approximately 1 inch.

Radio tubes of the foregoing general character have been on the market for a number of years and, in these, the cathode filament has been in the form of a straight wire, of the length mentioned, stretched between supports at its ends. Such a cathode filament has been surrounded by a helical grid electrode and a circular cylindrical plate electrode.

So far as I am aware, cathode filaments of the low-voltage and current ratings specified above have always been made straight, as above described.

However, it has been found that there is a perceptible hum, due to mechanical vibrations of filaments of the foregoing tubes, and,

for certain purposes, such as airplane radio sets, the fluctuations in the output current have been so severe as to produce noise of a very undesirable magnitude.

5 It is, accordingly, the object of my present invention to produce a radio tube having a cathode filament of only about one inch in length adapted for use with a single dry cell which shall have substantially no current 10 fluctuations of audible magnitude and frequency in its output circuit caused by mechanical vibration of said filament.

The minimization of the mechanical vibrations necessary to this result is attained by 15 supporting a cathode filament of the foregoing dimensions in the form of a V on short rigid support wires and enclosed within grid and plate electrodes also rigidly supported and braced.

20 In certain instances, higher-voltage cathode filaments, which were several inches in length, have been supported in the form of a V, but the purpose of this was not the prevention of microphonic noises. This will be 25 evident when it is considered that it is the running length of one side of the V which determines the frequency and magnitude of its mechanical vibration, and, accordingly, a V-shape filament each side of which is one inch 30 long will produce output current fluctuations of the same frequency and twice the magnitude of those produced by a single straight filament one inch long.

In the case of the above-described tubes 35 having filaments several inches long, the object of employing the V-formation was to shorten the end-to-end length of the radio tube itself, and thereby economize in cost and space requirement in the radio set. Thus, 40 the diameter of a radio tube employing a V-shape filament is not perceptibly greater than that of a radio tube employing a single straight filament; but, if a filament several inches long must be accommodated, the anode 45 and grid structure and the tube itself must be somewhat longer than the filament, if the latter is mounted in a straight-line position. In other words, with a filament two inches long the tube would have to be something 50 over three inches long. On the other hand, if the filament were bent back upon itself in the form of a V, the length of the tube could be reduced by approximately one inch 55 so that its extreme length would be only a little over two inches.

In quantity of production, the saving of glass and of time required to exhaust the interior volume of the tube is a considerable item and this led to the employment of the 60 V-shape where long filaments had to be used. Where the filament length was only one inch, any saving of cost in the foregoing directions from the use of a V-shape filament would be more than counter-balanced by the increased 65 mechanical difficulties met with in mounting

a V-shape filament of such small dimensions. Accordingly, it was considered more desirable to mount one-inch filaments in the straight-line position and, as above stated, this has always been the previous practice. 70 It is, accordingly, a novel feature, not appreciated by prior art workers, that it is advantageous to mount filaments, even as short as one inch, in the V-form, since such a mounting eliminates vibrations of audible frequency, notwithstanding the increased expense incident to the difficulty of thus mounting short filaments.

With the foregoing objects and principles in mind, my invention may thus be understood by reference to Fig. 1, wherein 1 is a radio tube of conventional form having a reentrant stem and a press, in which are sealed 7 short heavy inleading wires. The middle three of these wires support V-shape filament 3 having a length between its terminals of approximately $\frac{7}{8}$ of an inch. The middle wire of the three extends upward, parallel to the plane of the V-shape filament, but offset therefrom, and supports the apex 85 of the V on a resilient hook which is preferably coated with porcelain or silica to minimize conduction of heat away from the filament. The two inleading wires at each side of the three just mentioned support a helical 90 grid electrode of conventional form and the two outside leads support a plate in the form of a flattened cylinder. The support rods for the grid 4 and plate 5 are bent through 180 degrees just above the top of the anode and 100 are tied together with the middle support for the tip of the V by a bracing member 6 of glass into which they are fused. Both the grid 4 and the plate 5 are spaced as uniformly 105 as possible at all points from the cathode filament 3. All of the inleading wires are made as short as possible, consistently with the difficulties of manufacture and of preventing cracking of the cell from heat conduction. To give practical dimensions, I 110 have found good results to follow if all the inleading wires are 1.0 mm. in diameter and project $\frac{1}{4}$ inch above the glass of the press.

The electrode structure thus described is secured into the tube 1 in ways well known 115 in the art and the tube exhausted by methods now well standardized. The tube may be provided with any ordinary base adapted for installation in standard radio sets.

To provide a receiving tube adapted to have 120 its cathode heated by one quarter of an ampere of current drawn from a standard dry cell, a base filament of nickel $\frac{1}{8}$ of an inch long, 4.9 mils wide and 0.8 of a mil thick (or approximately 4 square mils in cross-sectional area), is coated with a mixture of equal parts of barium oxide and strontium oxide to the amount of approximately 5 milligrams per square centimeter of surface. This coating may be applied by making a 130

creamy paste of the above-mentioned oxides, dipping the filament into it, permitting it to dry and then heating it in carbon dioxide to a full red heat. If necessary, the dipping 5 operation should be repeated to produce the thickness of coating specified above. Such a filament will be found to be heated in vacuo to approximately 900 degrees centigrade by $\frac{1}{4}$ ampere and to emit electrons sufficient to 10 supply a plate current up to 10 milliamperes before reaching the saturation point or overheating to such an extent as on the average to decrease its operative life below 500 hours.

The cathode filament thus produced may 15 be welded to the two inleading wires at each terminal by methods well known in the art. The ends of the three supporting wires are so spaced that the filament is mounted in the form of a V, the two sides thereof preferably 20 at an angle of approximately 60 degrees. The helical grid 4 may be wound from 5 mil nickel wire, 28 turns per inch, in the form of a flattened cylinder, the plane faces of which are approximately $\frac{1}{16}$ of an inch apart and having 25 a length of $\frac{1}{2}$ inches and a breadth of $\frac{3}{8}$ inches. The anode 5 is likewise in the form of a flattened cylinder of 5 mil sheet nickel, the plane faces of which are approximately $\frac{5}{8}$ inches apart, its length being $\frac{1}{2}$ an inch 30 and its extreme breadth $\frac{1}{2}$ an inch. The V-shaped filament is positioned in the mid plane of both the grid and the anode cylinders. The grid electrode is of such a length as to extend slightly above and below the ends of 35 the cathode, and the plate electrode is similarly positioned.

It will be found that I have provided a structure for a hot cathode in an electrical-discharge tube in which the tendency to produce 40 mechanical vibrations of audible frequency is much less than in the case of the cathodes of similar length, voltage and current, employed in the prior art.

While I do not wish to be limited to the correctness of any theory, it is my belief that the absence of audible fluctuations in the output current of such tube as is herein described results both from the decreased amplitude of vibration of the filament itself and also from 50 the fact that its frequency of vibration is not one to which the ear is particularly sensitive. It is also believed that increased effectiveness in preventing microphonic fluctuations results from the employment of a supporting hook and rod at the apex of the V which extend in a plane perpendicular to that of the sides of the V, and that the seven short heavy support wires and their bracing are effective features in promoting the desired 55 result.

It will be realized that, although the foregoing dimensions are given as illustrative of one particular form of my invention which has been found effective in practice, these may 60 be varied when it is necessary to make other

conditions of heating-current and plate-current supply and voltage. It will also be recognized, under certain circumstances, that it may be desirable to support the filament with more than a single apex as, for instance, 70 in the form of a letter M. In such circumstances, the free length between supports of the sides of the filament would be correspondingly decreased resulting in a greater rigidity 75 and a higher period of mechanical vibration.

There is a further potential advantage inherent in the employment of short V-shaped cathode filaments in that their particular structure permits the use of alternating current of commercial frequencies for heating them without the production of harmonics capable of producing audible hum in the tube output circuits. It is well known in the art that if commercial frequency alternating current is employed for heating radio tube cathode filaments of the forms and dimensions hitherto used a periodic variation of audible frequency appears in the output current. It can be shown that this variation is the resultant of four factors:

1. The attraction of electrons emitted from the negative end of the filament by the end of the filament which is positive at any particular instant.

2. The effect of potential drop along the filament which rises and falls in the course of the alternating current cycle and which as I will hereinafter show produces fluctuations in the current from the anode.

3. The alternating magnetic field set up by the alternating current through the filament, which field deflects the electrons from the straight path which they would otherwise follow between the cathode and the anode.

4. The variations in temperature of the filament, resulting from the rise and fall of the alternating heating current in its cycle.

In receiving tubes of the many types, one or more of these causes may produce effects in the anode circuit so small as not to be of practical importance. It is probably only the three effects first mentioned which produce the hum actually heard in the case of ordinary receiving tubes. I have discovered that the instantaneous effects of the first and third factors listed are opposite in kind to those produced by the second, so that the latter tends to increase the anode current at the time each of the former tends to decrease it. The effect of the fourth, while a periodic quantity of the same frequency as the first and third, is probably dephased therefrom by nearly three quarters of a cycle so it cannot be exactly neutralized by either of the first three. Except for very thin filaments it is negligible in magnitude however.

I have further found that by properly proportioning the diameter, length, shape, resistivity, and temperature of operation of the filament, it is possible to make the aggregate

of the first and third effects substantially equal as well as opposite to the second, from which it follows that the net effect of all is made zero.

5 Turning to the various causes of hum enumerated above, their effects may be analyzed in connection with the diagram of Fig. 4, which may be considered as a view looking down on the anode and cathode 10 shown in Fig. 1. The mid-point of the cathode is taken as the axis of coordinates, and distances to the right of the point are represented by the quantity $+X$ while distances to the left thereof, are represented by 15 $-X$. The two ends of the filament are located at the distance $+L$ and $-L$ respectively. Between the mid-point of the cathode and the plate, the B-battery, having constant electro-motive force e_p , is connected. Between 20 the two ends of the cathode is impressed the electro-motive force $e = E \sin pt$. Considering the first cause of hum listed above, there will exist, at the surface of the cathode filament, an electric force due to the voltage between 25 opposite ends of the filament. This force will be uniform all along the filament due to the fact that both the distance and the potential difference between points opposite each other on the two sides of the V decrease at the same rate as the apex of the V is approached. This force may, as a first 30 approximation be considered to side-track certain electrons emitted from the cathode which otherwise would flow to the anode. Because 35 the voltage drop along the filament is small compared with that between the anode and cathode, the number of electrons thus side-tracked is relatively small.

40 The best known formulae for electron flow shows it to be approximately proportional to the square of the mean electric force between anode and cathode. Since we are here dealing with only a small correction term, the numbers of electrons side-tracked may thus 45 be considered to be proportional to

$$\left(\frac{E \sin pt}{2L}\right)^2.$$

50 Of the total number of electrons emitted per second by the filament a certain number N_0 would reach the anode if not side-tracked as aforesaid. The number which will be left available for flow to the anode when the voltage $E \sin pt$ is impressed on the cathode may be expressed as

$$N = N_0 \left[1 - \frac{KE^2 \sin^2 pt}{4L^2} \right],$$

60 where $E \sin pt$ is IR drop between ends of the cathode, $2L$ is the distance separating the ends of the cathode filament, and K is a constant.

65 Turning to the second cause of hum, the current flowing to the anode from the cathode

may be calculated with the aid of Fig. 2 by the use of the well known Langmuir formula.

$$i_p = Nle^2$$

70 Where i_p is current from a hot filament of length l to a radio tube anode, e is the potential difference between the cathode and the anode and N is proportional to the number of electrons available at the cathode.

75 In the case of a three-electrode tube the Langmuir formula takes the form

$$i_p = Nl(E_p + \mu E_g)^2$$

80 where E_p is anode voltage; E_g is grid voltage; and μ is the amplification constant of the tube; see page 417 of "Principles of Radio Communication" by J. H. Morecroft 1921, Wylie and Sons, New York, publishers.

85 Applying the foregoing formula to current between filament and anode in Fig. 2, the potential difference between the anode and any point on the cathode at a distance x from the mid-point thereof is represented by

$$e = e_p + \frac{x}{2L} E \sin pt$$

90 In accordance with the Langmuir formula, the current flowing to the plate from a small element dx will be represented by

$$di_p = N \left\{ e_p + \mu e_g + \frac{x}{2L} E \sin pt \right\}^2 dx$$

95 In ordinary receiving tubes, the filament voltage E is small compared to $(e_p + \mu e_g)$. Hence, this expression may be expanded and written

$$di_p = N(e_p + \mu e_g)^2 \left\{ 1 + \frac{3}{4} \frac{x}{L} \frac{E}{(e_p + \mu e_g)} \sin pt + \frac{3}{32} \frac{x^2}{L^2} \frac{E^2}{(e_p + \mu e_g)^2} \sin^2 pt \right\} dx$$

100 The effect of the alternating magnetic field is the third of the factors enumerated above as producing hum. In accordance with well-known electromagnetic laws an electron moving transverse to a magnetic field is deflected by a force which is perpendicular to its instantaneous movement and to the field and proportional to the product of its velocity and the magnetic field strength. The flow of an alternating heating current in applicant's V-shaped cathode produces 105 an alternating magnetic field encircling each limb of the filament and electrons moving radially outward toward the anode are deflected from the shorter path they would normally pursue and caused to follow a longer curved trajectory. The additional space charge incident to this longer path results in a diminution of the amount of current which the constant plate voltage can draw. The diminution is dependent upon 110

the absolute magnitude, but independent of the direction of the magnetic field at each instant; and as a first approximation it may therefore be set down as proportional to the square of the instantaneous value of the heating current. Since the filament is substantially a pure resistance the diminution of the electron current emanating from an elementary length, dx of the cathode filament can therefore be written

$$\Delta i_p = mif^2 dx = ME^2 \sin^2 pt dx$$

Where M is a constant depending on tube dimensions.

The current di_p which the preceding paragraph shows as emanating from the element dx should therefore be diminished by Δi_p , so that when the value derived in the first instance is substituted for N the net current from element dx is given by the expression

$$di_p - \Delta i_p = N_0(e_p + \mu e_g)^{\frac{3}{2}} \left[1 + \frac{3}{4} \frac{x}{L} \frac{E \sin pt}{e_p + \mu e_g} + \left(\frac{3}{32L^2} \frac{x^2}{(e_p + \mu e_g)^2} - \left(M + \frac{K}{4L^2} \right) \right) E^2 \sin^2 pt \right] dx$$

Upon integration this gives for the total anode current

$$i_p = N_0(e_p + \mu e_g)^{\frac{3}{2}} \left[2L + \left(\frac{L}{32(e_p + \mu e_g)^2} - \left(M + \frac{K}{4L^2} \right) L \right) E^2 (1 - \cos 2pt) \right]$$

This shows that the anode current consists of direct current component

$$N_0(e_p + \mu e_g)^{\frac{3}{2}} \left[2L + \frac{LE^2}{32(e_p + \mu e_g)^2} - \left(M + \frac{K}{4L^2} \right) E^2 L \right]$$

and an alternating current component

$$N_0(e_p + \mu e_g)^{\frac{3}{2}} \left[\frac{LE^2}{32(e_p + \mu e_g)^2} - \left(M + \frac{K}{4L^2} \right) E^2 L \right] \cos 2pt$$

which is of double frequency. It will be noticed that this alternating component has the character of an increment of the direct current which would flow if the B battery alone were supplying power to the circuit.

If

$$55 \quad \left[\frac{E^2 L}{32(e_p + \mu e_g)^2} - \left(M + \frac{K}{4L^2} \right) E^2 L \right]$$

is zero the alternating current component producing hum disappears.

Accordingly, I have conceived that it is possible to build a tube so proportioned that the quantity in parenthesis shall be zero and that no hum will be produced in such a tube.

For instance by varying L , the distance separating the ends of the V-shaped filament,

the hum due to the 2nd and 3rd factors above-enumerated may be reduced to zero.

It will be evident that a variation of L is not the only way of eliminating hum by making the quantity in the parenthesis zero. Thus, since the ratio of E to e_p and μe_g is not the same in the two terms, a variation of this ratio may be used to make the two terms equal. Thus, by varying the ratio of B battery voltage, the grid voltage and the filament voltage, the desired adjustment can be attained.

Figure 5 indicates a circuit suitable for employing my invention as above described, the reference characters 1, 3, 4 and 5 indicating the same tube elements as in Fig. 1. An input circuit is arranged to impress any desired modulated quantity upon the control electrode 4 and the anode 5 is connected to the cathode 3 through an output transformer 7, a blocking network comprising serially connected inductance 8 and condenser 9 in multiple with inductance 10, and a current source 11. By properly proportioning the relative magnitudes of the three elements 8, 9 and 10 the flow of undesired harmonics may be impeded in the output transformer, and this result will be aided by a condenser 12 which is shunted between anode 5 and cathode 3 as indicated.

While, in compliance with the patent statutes, I have described one embodiment of my invention, it will be understood that this is merely illustrative and that other embodiments of the principles thereof will be obvious to persons skilled in the art. I desire, therefore, that the following claim shall be limited only in accordance with its express terms and the state of the prior art.

I claim as my invention

In a vacuum tube, the combination of a grid electrode, a plate electrode, and a V-shaped electron-emissive cathode filament, said cathode filament having such resistance, normal heating current, and distance separating its ends, that the following formula is fulfilled

$$e_p + \mu e_g = \sqrt{\frac{8K}{32M + \frac{8K}{L^2}}}$$

where e_p is plate electrode operating voltage and e_g is grid electrode operating voltage, where M is the decrease of the plate current due to the magnetic effect arising when one volt is impressed between ends of the cathode filament, K is the decrease of plate current due to attraction of electron so the positive end of the cathode filament when one volt is impressed between ends thereof, and L is half the distance between the ends thereof.

In testimony whereof, I have hereunto subscribed my name this 5th day of October 1928.

LEE SUTHERLIN.
